UNITED STATES PATENT OFFICE.

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

TACK-SUPPLYING MECHANISM.

Application filed December 29, 1922. Serial No. 609,666.

This invention relates to tack supplying mechanism, and more particularly to means for maintaining a flow of tacks in a raceway. In the use of such mechanism a tack may sometimes become misplaced, so as to obstruct the flow of tacks along the raceway, for example by engaging the cover plate at the entrance to the covered portion of the raceway. It is customary, therefore, to provide means for dislodging misplaced tacks, a well-known form of such tack clearing means being shown in Letters Patent No. 1,107,337, granted on August 18, 1914, upon an application of R. F. McFeely. It sometimes happens, however, particularly if the raceway is full of tacks, that a misplaced tack will oppose such resistance to the movement of the tack clearing mechanism as to stop the operation of that mechanism, and the operator may fail to notice such a condition until the tacks in the raceway below the obstruction are used up and tacks are no longer delivered to the driving means. In attempting, moreover, to remove the obstruction by manual movement of the tack clearing mechanism the operator may bend one or more of the tacks in the raceway. It also sometimes happens that a tack becomes lodged between relatively movable parts of the tack clearing mechanism itself and thus renders it inoperative.

It is an object of the present invention to provide tack clearing mechanism which will not be subject to disadvantages such as those above mentioned and which will be more certain and effective in its action than heretofore. It is also an object to provide a construction which will be simple and inexpensive to build. In the illustrative embodiment of the invention the objects in view are accomplished by a novel construction and arrangement including provision for yield of a tack clearing member in response to abnormal resistance. While the invention, in some of its aspects, is not limited to the particular construction shown in respect to the manner of yield of the tack clearing member, important advantages, in some respects, are obtained by the use of a member of resilient material, for example spring metal, secured to its support or carrier. Among other advantages, this minimizes danger of interference with the operation of the mechanism by lodgement of tacks be-

tween relatively movable parts, and it also contributes to simplicity and economy in the cost of manufacture. A further feature is to be recognized in the provision of a tack clearing member which is yieldable transversely of the raceway and is angularly shaped to provide a projection for engagement with the tacks. If desired, a plurality of fingers may be arranged in a series, as herein shown, although the invention is not limited to such an arrangement. In case a finger fails to dislodge a tack which has become lodged in an abnormal position, the operation of the tack clearing means will not be stopped but the tack will be subjected to repeated impulses tending to dislodge it. Experience has demonstrated that this will usually result in dislodging the obstruction, and in any event the force applied will not bend the tacks.

The invention will now be more particularly described by reference to the accompanying drawings, and the novel features will then be set forth in the claims.

In the drawings,

Figure 1 is a perspective view of tack supplying mechanism including tack clearing means constructed in accordance with this invention, and

Fig. 2 is a vertical section illustrating more in detail the construction and mode of operation of the clearing mechanism.

The invention is herein illustrated in its application to tack supplying mechanism of a well-known type illustrated in said prior patent, including a rotary tack hopper 2 and a plurality of inclined race ways 4 the upper ends of which extend into position to receive tacks which fall from the hopper, the lower portions of the raceways having a cover plate 6 extending over them and provided with grooves 8 which permit the heads of the tacks to pass down the raceways to the usual tack separator. Mounted over the raceways and the cover plate 6 is tack clearing mechanism, comprising a rotatable carrier 10 arranged with its axis at right-angles to the raceways. Intermittent turning movements are imparted to the carrier 10 in the direction of the arrow by operating mechanism shown at 12, this operating mechanism being constructed as shown and described in the prior patent.

Mounted on the carrier 10 in operative

relation to each of the raceways 4 are a plurality of tack clearing members 14 arranged in a series to operate in succession. Each of the members 14, in the construction shown, comprises a finger of spring metal which is secured at one end to the carrier by a screw 16 and at its other end has an outturned projection 18 for engaging the tacks. The finger 14 is curved about the axis of the carrier 10 and extends from its fastening screw in a direction opposite to that in which the carrier rotates, and for the greater portion of its length the finger is spaced from the carrier so that it may yield transversely of the raceway, i. e., toward the axis of the carrier. The transverse projection 18 is herein shown as V-shaped to permit it to enter the groove of the raceway, and the cover plate 6 is provided with a similarly shaped groove 20 in the plane of the raceway along which the projection 18 moves before it reaches the raceway.

In the operation of the mechanism, in case a tack becomes misplaced, for example by engaging the edge of the cover plate 6 at the entrance to the covered portion of the raceway, so as to hold back the series of tacks in the upper portion of the raceway, it will be engaged and usually dislodged by one of the tack clearing fingers. If the finger should fail to dislodge the tack, the finger will yield and ride over the tack, and thereafter the tack will be engaged with repeated impulses as the fingers arrive successively in operative position until it is finally dislodged.

It will be evident that the invention is not limited to the use of fastenings of the particular character herein shown, but is applicable also to mechanism for utilizing nails and other like fastenings which the term "tack" as herein used is intended to include.

Having described the invention, what I claim as new and desire to secure by Letters Patent of the United States is:

1. In tack-supplying mechanism, the combination with a raceway for tacks, of a tack-clearing device comprising a finger of resilient material operatively movable in the general direction of its length along the raceway to dislodge misplaced tacks and having a tack-dislodging face at an angle to the length of a portion of the finger located in advance of said face in the operative movement of the finger, said finger being yieldable in a direction away from the raceway in response to abnormal resistance of the tacks to its movement along the raceway.

2. In tack supplying mechanism, the combination with a raceway, of a tack clearing member for dislodging misplaced tacks by relative movement between said member and the raceway in the direction of the length of the raceway, said member comprising a

finger arranged to extend in the general direction of the length of the raceway when in tack dislodging position and yieldable transversely of the raceway in response to abnormal resistance, the finger having at its outer end a projection extending at an angle to its length for engagement with the tacks. 70

3. In tack supplying mechanism, the combination with a raceway, of a tack clearing member for dislodging misplaced tacks by relative movement between said member and the raceway in the direction of the length of the raceway, said member comprising a finger formed of spring metal arranged to extend in the general direction of the length 80 of the raceway when in tack dislodging position and having a projection directed transversely of the raceway for engagement with the tacks. 85

4. In tack supplying mechanism, the combination with a raceway, of a tack clearing member mounted to move lengthwise of the raceway for dislodging misplaced tacks and arranged to swing yieldingly to permit it to ride over a tack that presents an abnormal 90 obstruction to its operative movement, said member having a V-shaped projection for engaging the tacks.

5. In tack-supplying mechanism, the combination with a raceway for tacks, of means 95 for dislodging misplaced tacks from the raceway, said means comprising a rotatable carrier and a tack-clearing finger of resilient material on said carrier so formed as to enter the raceway and to engage and dislodge 100 misplaced tacks and arranged to extend in the general direction of the length of the raceway when in tack-dislodging position, said finger being yieldable toward the axis of the carrier in response to abnormal resistance of the tacks to its movement along the raceway. 105

6. In tack supplying mechanism, the combination with a raceway, of means for dislodging misplaced tacks from the raceway, 110 said means comprising a movable carrier and a tack clearing finger of spring metal secured at one end to said carrier and having its other end spaced from the carrier and provided with a transverse projection 115 for engaging the tacks.

7. In tack supplying mechanism, the combination with a raceway, of means for dislodging misplaced tacks from the raceway, 120 said means comprising a carrier rotatable about an axis extending transversely of the raceway, and a tack clearing finger of spring metal secured to said carrier and having a transverse tack engaging projection thereon, said finger being yieldable toward the axis of the carrier in response to abnormal resistance to its operative movement. 125

8. In tack supplying mechanism, the combination with a raceway, of means for dis- 130

- lodging misplaced tacks from the raceway, said means comprising a carrier rotatable about an axis extending transversely of the raceway, and a tack clearing finger of spring metal curved about the axis of said carrier and spaced for a portion of its length from the carrier, said finger having on its outer end a transverse projection for engaging the tacks.
9. In tack supplying mechanism, the combination with a raceway, of means for dislodging misplaced tacks from the raceway, said means comprising a carrier rotatable about an axis extending transversely of the raceway, and a tack clearing finger of resilient material secured at one end to said carrier and extending in a curve about the axis of the carrier in a direction opposite to that in which the carrier is rotated, said finger having on its outer end portion a transverse projection for engagement with the tacks.
10. In tack supplying mechanism, the combination with an inclined raceway and a cover terminating below the upper end of the raceway, of means for clearing tacks from the entrance to the covered portion of the raceway, said means comprising a rotatable carrier mounted over the raceway and provided with a series of tack clearing fingers of resilient material having tack-engaging projections in the plane of the raceway.
11. In tack supplying mechanism, the combination with an inclined raceway, and a cover terminating below the upper end of the raceway and having a groove in the plane of the raceway, of means for clearing tacks from the entrance to the covered portion of the raceway, said means comprising a carrier rotatable about an axis extending transversely of the raceway, and a tack clearing finger of resilient material secured to said carrier and yieldable toward the axis of the carrier, said finger having a transverse projection to enter said groove in the cover.
10. In tack supplying mechanism, the combination with an inclined raceway and a cover terminating below the upper end of the raceway, of means for clearing tacks from the entrance to the covered portion of the raceway, said means comprising a rotatable carrier mounted over the raceway and provided with a series of tack clearing fingers of resilient material having tack-engaging projections in the plane of the raceway.
11. In tack supplying mechanism, the combination with an inclined raceway, and a cover terminating below the upper end of the raceway and having a groove in the plane of the raceway, of means for clearing tacks from the entrance to the covered portion of the raceway, said means comprising a carrier rotatable about an axis extending transversely of the raceway, and a tack clearing finger of resilient material secured to said carrier and yieldable toward the axis of the carrier, said finger having a transverse projection to enter said groove in the cover.

In testimony whereof I have signed my name to this specification.

BERNHARDT JORGENSEN.
